WEB CONTROLLER

Thomas Hamilton Grozier, Sydney,
New South Wales, AustraliaApplication March 10, 1933, Serial No. 660,328
In Australia March 24, 1932

15 Claims. (Cl. 271—2.6)

This invention chiefly relates to, improvements in printing machines and especially refers to improved apparatus for automatically governing or controlling register and web-tension in previously printed or premarked rolls of materials and more particularly for the synchronous unwinding and insetting thereof in connection with high speed rotary web printing, folding, cutting and assembling or the like machines having the same or lesser speeds.

My invention has been devised principally for use upon high speed rotary web perfecting presses which are employed in the production of newspapers, magazines, periodicals and the like, wherein several webs of paper (hereinafter called "main webs") are simultaneously and separately printed upon, brought together and thereafter slit and folded into a batch of sheets which constitute a newspaper or book.

20 In rotary web printing presses of the above-named character which usually operate at linear speeds of the paper webs in excess of 200 feet per minute, it will be readily understood that when the whole of the plate and impression cylinders are substantially of the same circumferential dimensions and are all positively coupled with each other by suitable gearing the proper register of individual or different main paper webs will be maintained. If, however, a previously printed web of paper (hereinafter termed the "inset web") possessing the same or different characteristics as to quality of paper and/or printing is required to be run into the product of a rotary web printing press so as to combine 25 with an ultimately form part of its delivered production, it has hitherto not been possible to maintain register as between the inset web and the main webs, printed in the rotary web printing press, by mechanism of simple and inexpensive construction that functions precisely and synchronously with the main driving members of the said press.

Under the most suitable and best conditions of operation, it is found that creep of the inset web in either a forward or backward direction takes place. Being accumulative, the register of the inset web with the main webs which was correct at the commencement of operations very soon becomes lost and the errors in register are often intensified by certain fluctuations of the tensions of the various webs at different periods of printing.

Moreover, shrinkage and/or stretch set up in the inset web by the difference of atmospheric conditions prevailing at the time of pre-printing

said web and of its final association with the main webs not infrequently affects adversely the register of the said inset web. Furthermore, variation in the smoothness or quality of the paper, or slip occasioned by improper adjustments of the paper-roll brake, or between the inset feeding-rollers, which draw the inset web into and through the machine towards the point of its association and assembly with the main webs issuing from the rotary printing press, are 10 all factors which more or less cause creep of the inset web and upset the correctness of its register.

This invention is also adapted for application to multi-colour printing machines (normally operating at moderate speeds) wherein one side 15 of the paper is printed and the web re-wound into a roll, which may afterwards be run in, cut into sheet form, printed on the reverse side, and then associated with the main webs of a rotary press or, alternatively, delivered in sheet formation at the delivery end of a multi-colour printing or like machine. My invention may also be employed in effecting correct register between a first printing on one side of a continuous paper web and a second or subsequent printing upon 20 the same side or the reverse side of the same web, or for otherwise registering a plurality of webs printed, or being printed and running toward folding, cutting, or assembling, or the like machines.

The invention, in addition to maintaining correct register of a pre-printed inset web in relation to other main webs, is further adapted to maintain correct tension in such a web. Moreover, it will maintain correct register and tension with high efficiency of pre-printed inset webs and/or unprinted webs consisting of perforated paper, water mark paper, or papers marked in other ways, or of similarly marked or perforated rolls of other materials in web form wherein said 30 marks or perforations are usually disposed at regular intervals or spacings along the length thereof.

Many efforts have already been made to provide means capable of effecting the requisite correct register, during the printing of a newspaper, between an inset web and the several main webs of a newspaper, such means ranging from simple hand-operated mechanisms to automatic mechanical, electric, and/or pneumatic control devices. It is recognized by those who are familiar with modern high-speed rotary web printing press operations that it is generally unsatisfactory or impracticable to use manually operated means for correcting the register of an inset web 40 45 50 55

on rotary printing presses operating at web speeds exceeding 200 linear feet per minute. Hand-operated means entail loss of time and waste of the product, and rectification is made 5 by trial and error or manual inspection which is regarded as being an impracticable method of operation or procedure when applied to high speed machines. Although manually operated register correction means are unsuitable for use 10 with high-speed rotary printing presses they may, nevertheless, be successfully applied to printing presses operating at speeds less than 200 feet per minute and in which extreme accuracy of register in the delivered production is not essential. 15

In the case of automatic electric and/or pneumatic and combination mechanical means designed to effect register-correction, it is well known to those versed in the art of printing 20 25 30 35 40 45 50 rection means combined with the register and web-tension governing means under the influence of the photo-electric means is adapted to retard the inset feeding-rollers relative to said printing and other cylinders. The variations in the tension of the inset web caused by the advancing or retarding of the feeding-rollers are at once compensated for by the automatic brake mechanism which correspondingly varies the brake pressure on the reel bar or paper-roll spindle. By the use of such coating automatic braking and register and web-tension governing means and register correction means, I have found that correct register of the inset web with the main webs can be automatically maintained with maximum efficiency and a minimum of operative frequencies.

Briefly stated, the objects of the present invention reside, inter alia, in the provision of the following:

(a) Improved apparatus, including web-tension controlling means and an electro-magnetically and web-actuated register governor, adapted to automatically maintain correct tension and register of a previously printed or marked inset web when the same is being run into and combined with the regular product of a modern high speed rotary web perfecting press.

(b) Automatic web-tension controlling means and an automatic electro-magnetically and web-actuated register governor of simple and relatively inexpensive construction, which can be incorporated in rotary web printing presses or like machines during manufacture, or applied to such presses or machines as are already installed and in regular use.

(c) Automatic web-tension controlling means and an automatic electro-magnetically and web-actuated register governor which are specially adapted for (but are not restricted to) high speed rotary web printing presses normally operating at speeds in excess of 200 feet per minute, and which are exceedingly efficient for maintaining the correct tension and running register of an inset web with maximum precision at the highest known speeds of newspaper production.

(d) A brake on a reel bar or paper-roll spindle carrying a pre-printed or marked roll, said brake being automatically controlled by the tension of the pre-printed paper web being unwound from the said roll and inset and associated with another web or other webs being freshly printed, and then cut and folded in the rotary web printing press.

(e) Automatic electro-magnetically and web-actuated register governing means associated with inset feeding or drawing rollers, which are positively inter-connected by gearing with the printing cylinders of a rotary web printing press and have the same surface speed as said cylinders, said governing means being adapted to advance or retard the inset feeding-roller bodies to maintain correct register of a pre-printed inset web with another web or other webs being freshly printed, and then cut and folded in the rotary web printing press.

(f) Photo-electric detection means in combination with synchronized timing means and automatic electro-magnetically and web-actuated register governing means, said photo-electric detection means being adapted to detect errors in the register of the pre-printed inset web at the moment of their inception and to transmit electrical impulses to the said synchronized timing

means and thereby to said governing means to momentarily advance or retard the said inset web to counteract or correct the errors in the register of said inset web.

(g) Means for projecting a beam of light onto or through a travelling pre-printed or otherwise marked inset web or in the path of register indication marks or perforations on said web, photo-electric means positioned adjacently to the travelling web and adapted to intercept the beam of light after the same has impinged on or penetrated the travelling web, an amplifying and relaying circuit associated with the photo-electric means, synchronized timing means connected with the amplifying and relaying circuit and synchronized with the printing cylinders and general mechanism of the printing press, feeding-rollers for the inset web having the same surface velocity as the printing cylinders, and electro-magnetically and web-actuated register governing means synchronously driven with the inset feeding-rollers and connected with the said timing means and adapted when energized by an amplified and relayed electrical impulse transmitted by the photo-electric means to advance or retard the inset feeding-roller bodies to maintain correct register of said inset web.

(h) An improved automatic register governor synchronously driven with and by the press or other main machine mechanism and including an infinitely variable adjustable coupling connecting inset web feeding-roller bodies with the said main machine mechanism, said infinitely variable adjustable coupling being automatically adjustable to advance or retard the inset feeding-roller bodies relatively to the press mechanism to maintain correct register of the inset web.

(i) An improved automatic register governor in which all movements and adjustments are of a rotative character, whereby said governor is adapted to operate efficiently at the highest known speeds of newspaper production.

(j) An improved automatic register governor synchronously driven with and by the press or other main machine mechanism and connected with inset web feeding-roller bodies, and an inset web reel brake automatically controlled by the inset web-tension, said register governor and automatic brake comprising interdependent means which are co-active in maintaining correct register in the inset web.

My invention is fundamentally based on preventive means, supplemented by corrective means, whilst existing register-correction means are not preventive in any way, but are wholly or merely corrective to a certain degree or extent and are thus limited to relatively low operative efficiencies; coupled with comparatively high costs of manufacture, installation, operation and maintenance. My invention also provides means whereby the present necessity of non-synchronous speeds in relation to the "inset" feeding-roller drive and main drives of the press are now dispensed with. The invention also combines the use of a selenium-bridge or photo-electric means for the instantaneous, accurate and precise detection of register errors indicated by the slightest displacement from their normal positions of small regularly spaced, printed and/or more or less opaque or transparent marginal marks and/or perforations in the inset web, such displacements of the marks or perforations being adapted to render active the selenium-bridge or photo-electric means to operatively control the aforesaid register governing and register correc-

tion means without the use of extraneous independent or interdependent non-synchronous control media of a complex character.

In some instances, especially when constructional cost is of primary importance and when machine speeds are relatively low and definite accuracy of register is not essential, register and web-tension governing means may be dispensed with and my register correction means may be used alone. Notwithstanding that my invention is primarily intended for automatic operation, the register correction means may be controlled by direct manual operation, or it may be controlled by electro-magnetically operated means which are governed by hand-actuated switches.

The invention will be more clearly understood by reference to the accompanying drawings wherein:—

Fig. 1 is a side elevation illustrating the invention as applied to a rotary web printing press or like machine.

Fig. 2 is a transverse section taken on the line 2—2 of Fig. 1.

Fig. 3 is a sectional plan of the automatic register governor gearing.

Fig. 4 is a sectional view taken on the line 4—4 in Fig. 3.

Fig. 5 is a longitudinal section on the line 5—5 in Fig. 4.

Fig. 6 is a transverse section of a detail of Fig. 5.

Fig. 7 is a diagrammatic view of photo-electric detection means, an amplifying and relay circuit, and the timing means associated with the photo-electric means and with the automatic register governor gearing.

Fig. 8 is an end view of alternative electromagnets for controlling the automatic register governor gearing.

Fig. 9 is a plan view illustrating an alternative form of automatic register governor gearing.

Fig. 10 is a diagrammatic end view of Fig. 9 showing the solenoids and associated parts of said alternative form of automatic register governor gearing.

Fig. 11 is a side elevation of re-winding apparatus suitable for use in conjunction with the invention.

Reference being made initially to Figs. 1 to 8 of the drawings which illustrate a preferred form of my invention, the numeral 1 indicates a roll consisting of a web W of pre-printed or watermark paper or like material having opaque and/or transparent marks and/or perforations disposed at regular intervals throughout the length thereof, of which web is wound upon a reel bar or paper-roll spindle 2 supported in bearings 3 fitted in side frames 4 and 5 which may form or become part of a rotary web printing press.

For the purpose of regulating the tension of the paper web W, while said web is being drawn from the roll 1 and passed through the printing press, there is fixed to the reel bar or spindle 2 a brake drum 5a upon the periphery of which bear oppositely positioned brake shoes 6 and 7. The brake shoes 6 and 7 are mounted on arms or levers 8 and 9 which are fulcrumed on pivots 10 and 11 respectively.

The lever 9 is provided with an arm or extension 12, which is bent upwardly and contacts near its upper end with a cam roll 13 carried on a shaft 14. The arm 12 is maintained in contact with the cam roll 13 by a spring 15, one end of which is attached to said arm while the opposite end of said spring is connected to a hook 16 fixed in the brake lever 8.

The shaft 14 is pivotally mounted in the side frames 4 and 5 and it is provided with spaced parallel arms 17, disposed on opposite sides of the web W and supporting a floating roller 18, which bears upon and maintains the tension of the web W, and is hereinafter termed the compensating tension roller. Mounted in a convenient position on the shaft 14 is a rod or lever 19, the longer arm 20 of which carries an adjustable counter-weight 21, while the shorter arm 22 is connected to the plunger 23 of a dashpot 24 fixed to the side frame 4.

The web W is drawn from the roll 1 and passes over a compensating or spring roller 25 and a guide roller 26, thence beneath the compensating tension roller 18 and over a guide roller 27. From the guide 27, the web W passes around and between inter-gearied inset feeding-rollers or drawing-rollers 28 and 29, and is then directed by guide rollers 30 and 31 to subsequently become inset and associated at the former roll of the folder with the other web or webs then being freshly printed in the press. The web W is preferably made to wrap around large peripheral portions of the inset feeding-rollers 28 and 29 for the purpose of eliminating slip and maintaining the maximum control in governing correct register of the inset web.

The feeding-rollers or drawing-rollers 28 and 29, which may be of any preferred diameter, are nevertheless diametrically and circumferentially proportioned to correspond with the ratio of the printing cylinders of the rotary web perfecting press printing the main product of the newspaper with which the pre-printed inset web W is to be associated and assembled at the folding, cutting, and delivering section of the machine. The feeding-rollers 28 and 29 are in close contact with each other and are positively geared together to rotate at the same speed, but in opposite directions by equal spur gears 32 and 33, see Fig. 2.

The feeding-rollers 28 and 29 are supported by transverse shafts 34 and 35, and said feeding-rollers are positively connected with and are driven by the mechanism of the press. In thus connecting and driving the feeding-rollers 28 and 29, a shaft 36, which is positively driven by the press mechanism, carries a bevel gear 37 that meshes with a bevel gear 38 mounted on a transverse shaft 39.

Fixed to the bevel gear 38 is a chain belt pulley 40 which is operatively connected with an expanding chain belt pulley 41 (of conventional type such as shown, for example, in Patent No. 598,107, issued February 1, 1898), fast on the shaft 34 by a chain belt 42 which combination comprises infinitely variable pre-set speed means. If preferred, a vertical shaft 43 rotatably supported in bearings (not shown) mounted on the press frame 5, may in certain instances be used instead of the infinitely variable pre-set speed means comprising the chain belt 42 and pulleys 40 and 41. The lower end of the shaft 43 is provided with a bevel gear 44, while the upper end of said shaft carries a bevel gear 45 which meshes with a bevel gear 46 fixed to the shaft 34.

The shaft 36 is so connected with the press mechanism, and the bevel gears 37 and 38 and the variable speed chain belt pulleys 40 and 41 (or the fixed speed bevel gears 44, 45 and 46) are so designed and proportioned that the surface or peripheral speed of the feeding-rollers 28 and 29 is exactly equal to the surface or peripheral speed of the printing cylinders (not shown) of the main press or like main mechanisms.

The bevel gear 37 may be loosely mounted on the shaft 36, and said gear may be provided with a clutch element 47 adapted for engagement with a co-acting clutch element 48 slidably and non-5 turnably mounted on the shaft 36. Accordingly, the slideable clutch element 48 may be engaged with or disengaged from the clutch element 47 to enable the bevel gear 37 to drive the feeding-rollers 28 and 29 or to stop said rollers, as and 10 when required.

10 The shaft 34 is journaled at one end in a bushing 49 fixed in the side frame 4, and the opposite end of said shaft extends through and is free to turn in a sleeve 50, which is rotatably mounted
15 in a concentric bushing 51 fixed in the side frame 5, see Fig. 2.

3, see Fig. 1. The feeding-roller 28 is fitted at one end with a bushing 52 which is free to rotate on the shaft 34, and said feeding-roller at its opposite end is 20 securely fixed to the sleeve 50 in any preferred manner. In one method of securing the sleeve 50 to the feeding-roller 28, said feeding-roller may be provided with a hub 28a into which said sleeve is tightly fitted and is non-turnably secured by 25 a key or feather 28b and a set-screw 28c, see Fig. 5. Accordingly, it will be understood that the feeding-roller 28 is not fixed to the shaft 34, but is free to turn thereon in the manner hereinafter described. The other feeding-roller 29 is fixed to 30 the shaft 35, which is rotatably mounted in bushings in the side frames 4 and 5 as clearly shown in Fig. 2.

The feeding-rollers 28 and 29 at all times rotate together, being constrained so to do by the equal spur gears 32 and 33. Moreover, any advancing or retarding movement imparted to the roller 28 will also be transmitted by the gears 32 and 33 to the feeding-roller 29, as will be readily understood.

40 The shaft 34 is extended through and projects a required distance from the outer side of the side frame 5, and its outer end is supported in a sleeve 53 which is rotatably mounted in a frame 54 rigidly secured to the side frame 5.

45 The sleeve 53 is co-axially aligned with the sleeve 50, and said sleeves 50 and 53 form lateral extensions or hubs of a hollow structure or casing 55. The hollow structure or casing 55 may be of cylindrical form, and it may be constructed 50 in one piece or casting having sleeves 50 and 53 formed integrally with it, as clearly shown in Fig. 5. Alternatively, the said hollow structure or casing may be made in similar or dissimilar sections, or in halves, which may be fixed together, as by bolts or other suitable fastenings. Again, the said structure or casing may be made as an open frame as hereinafter described or it may be constructed in other approved manner. The hollow structure or casing 55 is rigidly connected by the sleeve 50 to the feeding-roller 28 so that said feeding-roller, the hollow structure or casing 55 and the sleeves 50 and 53 are capable of rotation about the shaft 34. Moreover, any turning movement in forward or backward direction that is imparted to the structure or casing 55 will be transmitted by the sleeve 50 to the roller 28 and accordingly to the roller 29.

26 and accordingly to the rear 17. Situated within the casing 55 and rigidly fitted by a key 56a or otherwise nonturnably secured to the shaft 34 is a worm wheel 56 engaged by a worm 57. The worm 57 is provided at its opposite ends with co-axially aligned journal shafts 58, which extend through and are rotatably mounted in bearing supports 59 fixed to or integrally formed with the casing 55. The shafts

58 are of somewhat less diameter than the worm 57 so that the latter is provided with shoulders 60 which contact with the bearing supports 59. The bearing supports 59 prevent endwise movement of the worm 57, and said supports form abutments for thrust imparted to said worm by the worm wheel 56. 5

The worm wheel 56 and worm 57 are of self-locking variety so that the worm wheel 56 is incapable of rotating the worm 57, although the 10 said worm itself may be rotated. Moreover, as the worm wheel 56 is rigidly fixed to the shaft 34, which is connected as previously described to the driving mechanism of the press, the worm 57 cannot rotate the worm wheel, 56. Accordingly, if the worm 57 be rotated it will travel around the periphery of the worm wheel 56 and it will carry with it the bearing supports 59, casing 55, and therewith the feeding-roller 28, which feeding-roller will by the gears 32 and 33 20 correspondingly rotate the feeding-roller 29 in the required direction, either to advance or retard said feeding-rollers 28 and 29.

The worm wheel 56, worm 57 and the bearing supports 59 form a positive driving connection 25 between the shaft 34 and the casing 55 and accordingly between said shaft 34 and the feeding-roller 28, which feeding-roller is rigidly connected to said casing 55 by the sleeve 58. Moreover, the worm wheel 56 and worm 57 form in 30 effect an infinitely variable adjustable coupling whereby the casing 55 and the roller 28 may be rotated more or less about the shaft 34. Thus, by turning the worm 57 in one direction the casing 55 and the feeding-roller 28 may be moved 35 in the direction of rotation of the shaft 34 or advanced, while rotation of the worm 57 in the opposite direction will cause said casing and said feeding-roller to be retarded relatively to said shaft. As the shaft 34 is positively geared with 40 the printing cylinders and other portions of the press mechanism, advancement or retardation of the feeding-roller 28 and the feeding-roller 29 geared with said feeding-roller 28 will also take 45 place relatively to said printing cylinders and other portions of the press mechanism, but the synchronous speed of the shaft 34 will remain unaffected by such movements of the feeding-rollers 28 and 29.

Accordingly, if the inset web W should lag 50 behind the main web or webs being freshly printed and/or cut and folded, said inset web may be advanced and set in correct register with the other main web or webs by appropriate rotation of the worm 57 and consequent advancing of the 55 feeding-rollers 28 and 29. On the other hand, if the web W should creep ahead of the main web or webs being printed and/or cut and folded, rotation of the worm 57 in the opposite direction will retard the feeding-rollers 28 and 29 60 sufficiently to restore the correct register.

Fixed securely to the co-axially aligned shafts 58 of the worm 57 are bevel gears 61, with which are meshed bevel gears 62 fixed to spindles 63 and 64 extending transversely across and rotatably mounted in the casing 55. The spindles 63 and 64 project laterally from the sides of the casing 55 and their outer ends are provided with means, hereinafter described, whereby said spindles may be rotated more or less at certain times. 70

Fixed in or formed integrally with the casing 55 and positioned oppositely to the worm 57 is a counterweight 55a of sufficient magnitude to balance said worm 57, the bearing supports 59, the bevel gears 61 and 62 and the other 75

- parts which rotate with the worm 57 about the axis of the shaft 34. Accordingly, the casing 55, notwithstanding the eccentric mounting of the worm 57 and the parts associated with said worm, is adapted to rotate smoothly and without vibration. The casing 55 and all associated parts may be conveniently housed or guarded by a fixed casing 55b attached to the side frame 5. It is mostly and generally desirable to provide 10 co-operative register detection means. For this purpose a photo-electric cell 65 or like device and an exciting lamp 66 are fixed in a convenient position near the inset web W, preferably on the delivery side of the feeding-rollers 28 and 29, as, 15 for example, between the guide rollers 30 and 31. The exciting lamp 66 is mounted in conjunction with a suitable optical device 67, and said lamp and optical device are adapted to throw a beam of light upon the inset web W in the path of a 20 series of regularly spaced opaque printed marks, semi-transparent water marks, transparent perforations, or other opaque, semi-transparent, or transparent indicating marks, all of which are indicated by the letter M made in or on said web, 25 and preferably located on the centre margin of the inset web. The said indicating marks represented by M are of greater opacity or transparency and have less or more reflective power (as the case may be) than the parts of the web 30 W extending between said indicating marks. The photo-electric cell 65 and the exciting lamp 66 may be positioned on the same side as, or on opposite sides of, the travelling inset web W— see Fig. 1.
- 35 When the photo-electric cell and the exciting lamp are located on the same side as the travelling web W, the beam of light, after reflection from the said web W, impinges upon the photo-electric cell 65, and said beam owing to the lower 40 reflective power of opaque marks M is more or less intercepted or momentarily eclipsed by said opaque marks as they move past the photo-electric cell 65.
- 45 While the unmarked parts of the web W between the indicating opaque marks M reflect the beam of light upon the photo-electric cell 65, said photo-electric cell remains inactive. However, when the beam is momentarily eclipsed or clouded by the passage of an opaque mark M, 50 the photo-electric cell 65 becomes instantaneously operative and transmits an electrical impulse.
- 55 It will be understood that when the indicating marks M are transparent or relatively so, the photo-electric cell and the exciting lamp are positioned on opposite sides of the travelling web W, and said marks M, in passing between the lamp and the photo-electric cell, allow the beam of light from the said lamp to penetrate 60 through the travelling web and impinge upon the said photo-electric cell for the transmission of an electrical impulse. In either of these cases, the electrical impulse, so transmitted, after passing through a suitable amplifying and relaying circuit "C", (which may be located as shown in Fig. 1) and through timing means "T", under certain conditions energizes special electro-magnets, as hereinafter described, which function to 65 operate the infinitely variable adjustable coupling comprising the worm 57 and worm wheel 56 and associated parts to advance or retard the feeding-rollers 28 and 29.
- 70 Fig. 7 shows a suitable amplifying circuit 65a and a relaying circuit 65b (said circuits being indicated generally by "C") for modifying the im-

pulses transmitted by the photo-electric cell 65, but it is to be understood that this circuit "C" is shown by way of example only as other suitable circuits may also be employed for the purpose.

5 Fixed to the frame 54 is an insulating block or distributor stator 68, through the centre of which extends the shaft 34. The shaft 34 projects outwardly from the face of the stator 68, and slidably and non-turnably fixed on said shaft, as by means of a key 69a, is an insulating arm or distributor rotor 69. Fixed detachably on the stator 68 by suitable clips or fastenings (not shown) is an insulating cover 70, which supports a terminal 71 having electrically associated with it a spring-actuated brush 72. The brush 72 bears upon a 15 metal strip 73 fixed in the rotor 69, and said metal strip is electrically connected with a spring-pressed brush 74, which is carried around by the rotor 69 and bears constantly upon the face of the stator 68. Mounted in said stator 68 are 20 contact segments 75 and 76 (indicated by broken lines in Fig. 3) and shown by full lines in Fig. 7. The outer ends of the segments 75 and 76 are flush with the face of the stator 68, and the inner ends of said segments 75 and 76 are connected to terminals 77 and 78, respectively. The brush 74, in rotating, passes over the segments 75 and 76 and connects said segments one at a time with the terminal 71 so that said terminal is accordingly connected alternatively to the 30 terminals 77 and 78.

35 The distributor having the stator 68 and co-acting rotor 69 is of the type used for ignition purposes on internal combustion engines. For convenience of illustration, a wipe type of distributor has been selected, but it will be understood that distributors having cams and spring contacts, or other distributing means or members may be used if preferred without restricting the ambit of this invention. The distributor described 40 forms timing means "T" which co-act with the photo-electric cell 65 and constitute part of the system, hereinafter described, which maintains the inset web W in correct register.

45 Positioned on opposite sides of the casing 55 and fixed respectively to the side frame 5 and the frame 54 are annular electro-magnets 79 and 80, which are disposed concentrically about the shaft 34 and may be constructed in different ways without departing from the spirit of this invention. In one suitable form, each of said electro-magnets comprises two discs 81 and 82 of iron or other highly permeable magnetic metal, which discs are spaced in parallel relation on opposite sides of an annular distance piece 83. The discs 55 81 and 82 form channels 84 and 85 on the inner and outer sides of the distance piece 83, see Figs. 5 and 6.

55 The outer channel 85 of each of the electro-magnets 79 and 80 accommodates a winding 86, 60 and when an electric current is passed through said winding the discs 81 and 82 become magnetized and have opposite polarities. An annular magnetic field is set up between the discs 81 and 82, and it extends across the inner channel 65 84.

65 Mounted on the outer ends of the hereinbefore described spindles 63 and 64 are discs 87, which are carried round by said spindles as the casing 55 rotates. The discs 87 are of iron, and portion 70 of said discs is positioned within the inner channel 84 of the electro-magnets 79 and 80, see Figs. 4 and 5. The discs 87 are of such diameter and thickness that their peripheries and sides are separated from the inner surface of the annular dis- 75

tance piece 83 and the inner sides of the iron discs 81 and 82 by short distances or air gaps 78a so that said discs do not contact with the sides or periphery of the channel 84 while they are moving in circular orbits about the axis of the shaft 34.

The discs 87 move idly within the respective annular channels 84 until one of the electro-magnets 79 or 80 becomes energized, whereupon the annular magnetic field thereby set up will pull or drag upon the corresponding disc 87 and rotate the same together with the spindle 63 or 64 upon which said discs are mounted.

The spindle 63, upon being rotated, will revolve the worm 57 by means of the bevel gears 61 and 62. If the spindle 64 be turned in the same direction as that in which the spindle 63 was rotated, the worm 57 will also be revolved, but it will turn in the reverse direction.

As previously described, rotation of the worm 57 in one direction will advance the feeding-rollers 28 and 29, while rotation of said worm in the opposite direction will retard said roller. Accordingly, it will be obvious that while the two discs 87 are moving in the same direction, if one of the electro-magnets 79 or 80 be energized the feeding-rollers 28 and 29 will be advanced, while if the other electro-magnet be rendered active said feeding-rollers will be retarded.

The annular electro-magnets 79 and 80, instead of having peripheral windings 86 and being energized throughout to form an annular magnetic field, may be provided with one or more energizing coils 88, see Fig. 8. The electro-magnets 79 and 80 may accordingly be provided with one or more energized or active arcuate segments, and such segment or segments may be designed to exert a definite pull or force on the discs 87. Moreover, the electro-magnets 79 and 80 may be formed completely of relatively short segments which may be energized to form annular magnetic fields of equal intensity at all parts of the circumferences of said electro-magnets.

In the case of certain low speed machines in which the delivered production does not necessitate extreme accuracy of register, the energization of the electro-magnets 79 and 80 may be controlled manually, and the photo-electric cell 65, the exciting lamp 66, the optical device 67, and the amplifying and relay circuit "C" may be dispensed with. When so arranged for manual operation, the electro-magnets 79 and 80 and the timing means "T" may be associated in electrical circuits controlled by hand operated switches 79a and 80a, as indicated by broken lines in Fig. 3.

In Figs. 9 and 10, there is shown modified automatic register governing means more particularly suitable for relatively low or moderate printing press speeds which may be less than 200 surface feet per minute, said governing means being also adaptable for application to and operation with cutting, assembling, or folding machines operating at comparatively low speeds in connection with rolled webs of pre-printed, water mark, or perforated papers, or other materials in web form which are similarly marked at more or less regular intervals or spacings along the length of said webs.

The frames 5 and 54, hereinbefore described, carry solenoids 89, which are concentrically mounted on said frames at suitably spaced intervals and are fitted with plungers 90 of magnetic material. The windings of the solenoids 89 on the frame 5 may be connected with the distributor terminal 71, while the windings of said solenoids

on the frame 54 may likewise be connected with the distributor terminal 78. The windings of the solenoids 89 are thus connected at one end of their windings through the synchronous timing means, hereinbefore described, with the amplifying circuit 65a and relaying circuit 65b of the photo-electric means 65, while the opposite end of their windings are also associated with said circuit. The spindles 63 and 64, in lieu of the iron discs 87, are provided with star wheels 91, and a frame 94 alternative to the said casing 55 may be provided with cams 92 which are fixed to and project from the opposite sides of said frame.

Upon the solenoids 89 on either the frame 5 or the frame 54 becoming energized, the plungers 90 thereof are thrust outwardly into the concentric path of the corresponding star wheel 91, which is thus rotated to turn the spindle 63 or 64 to rotate the worm 57 to either advance or retard the feeding-rollers 28 and 29 in the manner hereinbefore described.

The cams 92 are mounted on the casing 55 or frame 94 in such positions that they follow or trail behind the star wheel 91 that is positioned on the same side of said casing. When the solenoids 89 become de-magnetized after the adjustment of the feeding-rollers 28 and 29 has been effected, the cams 92 return the plungers 90 into their normal positions in said solenoids.

In some cases in which definite accuracy is not important or is not required, and wherein it is desirable to provide simple, reliable and inexpensive register correction means for low speeds, the solenoids 89 and timing means "T" may be dispensed with and the star wheels 91 may be actuated by plungers or spindles, such as 90, which are pushed into the concentric path of said star wheels by hand. Alternatively, similar hand-operation may be effected electrically by switches 89a and 89b, see Fig. 9, in which case the solenoids 89 are retained together with timing means "T".

In Figs. 9 and 10, there is shown a modified structure or frame 94 which is alternative to the aforesaid casing 55 and is likewise adapted to support the worm 57 and the parts co-acting therewith. In this modified structure for supporting the worm, a disc 93, having the sleeve 50 integrally formed with it and connected to the feeding-roller 28 as hereinbefore described is loosely mounted on the shaft 34. To the disc 93 the worm bearing supports 59 are secured, and a bracket 94 is fixed to said disc and rotatably supports one end of the spindles 63 and 64, the opposite ends of said spindles being rotatably mounted in the disc 93. The bracket 94 is integrally formed with the sleeve 53, which as previously described is mounted in the frame 54. In some cases, the disc 93 may be fixed directly to the end of the feeding-roller 28 or to a shoulder or flange or other extension thereof.

The web to be associated or inset with the main web or webs when these are being freshly printed in a rotary web press is pre-printed in said press, or in any other preferred manner, and may then be rewound onto a paper-roll spindle or reel bar 2. For the purpose of rewinding the pre-printed inset web (indicated by chain dotted lines in Fig. 11), the side frames 4 and 5 may be provided with aligned slots 95, into which bearings 96 carrying the reel bar 2 are slidably fitted. The reel bar 2 is then rotated by rollers 97 and 98 through spur gears 99, 100, 101, bevel gears 102 and 103, clutch elements 104 and 105 and shaft 75

106, which shaft forms an extension of the shaft 36 hereinbefore described.

Weights 107 slidably fitted in the slots 98 are carried by the bearings 96 and maintain even pressure on the reel bar 2 during the re-winding of the previously printed web, which then travels above and out of contact with the feeding-rollers 28 and 29 as shown in Fig. 1.

10 The positions occupied by the re-wound pre-printed roll of paper web are indicated by broken lines in Figs. 1 and 11 in which are shown, respectively, the rewinding roll 1a and rewinding roll 1 and their approximate correlative locations.

15 The frames 4 and 5 are fixed and braced together in suitable manner, and they may be attached to or formed with the main frames of a rotary web press. Preferably, said frames are located in the vicinity of the assembling, associating, folding, cutting and delivery mechanism of the said press.

20 I will now describe the operation of my invention constructed as shown in Figs. 1 to 8 and Figs. 9 and 10. The inset web W is pre-set in correct register with the main web or webs being freshly printed in the rotary web press in such manner that the regularly spaced opaque or transparent register indication marks M (preferably made on the centre margin of the inset web W) are synchronized with the signatures of the main web or webs. Moreover, in the preliminary adjustment of the inset web W, the said register indication marks M are so positioned, that in passing the photo-electric cell 65 they will, if opaque, eclipse or obscure more or less the beam of light falling on said cell when the timing arm or distributor rotor 69, in rotating, occupies a neutral or non-contact position between the timing segments or contacts 75 and 76, see Fig. 7.

25 If the said indication marks N are transparent, as with perforations, or semi-transparent as with water marking, the light beam may penetrate the web W and impinge on the photo-electric cell 65 when the timing arm or distributor rotor 69 occupies its neutral position.

30 At the commencement of the insetting operation, the paper-roll 1 consisting of the re-wound pre-printed inset web W is of maximum diameter and the floating compensating tension roller 18 occupies its lowest position shown in Fig. 1.

35 When the rotary press is set in motion, the inset web W initially in correct register is drawn from the roll 1 by the inset feeding-rollers 28 and 29, which as previously described are positively driven by the press mechanism and are synchronized with and have substantially the same surface velocity as the associating or former rollers, the printing, cutting and folding cylinders, and other parts of the press mechanism around or between which the inset W passes or contacts with. By means of the variable speed pulleys 43 and 41 and chain belt 42, the inset feeding-roller speeds may be precisely adjusted to conform with the main press printing cylinders which may have altered circumferentially. As the linear speed of the inset web W is then identical with the said surface velocity the several guide rollers, the compensating tension roller 18, and the compensating roller 25 all have correlative peripheral speeds.

40 Accordingly, the motion of all of said printing cylinders and inset feed and guide rollers is perfectly synchronized. Moreover, the energizing of

the photo-electric cell 65 by the obscured or the transmitted beam of light occurs at the instant that the timing arm 69, during each revolution, occupies its neutral position between the contacts 75 and 76. However, notwithstanding that the 5 photo-electric cell is so energized and that said photo-electric cell accordingly sets up an electric-motive force, no current can flow through the winding 86 of the electro-magnets 79 and 80, or the solenoids 89 (if the latter be used) until such 10 time as the timing arm 69 (or the brush 74) contacts with one of the contact segments 75 and 76.

15 I have found that when a pre-printed inset web W is drawn from a re-wound roll 1 having its paper-roll spindle (or reel bar) 2 governed by an 15 automatic brake constructed as hereinbefore described, erratic oscillative fluctuations of speed or alternative quickening and slowing of the inset web are prevented. However, I have also found that if the inset web has shrunk during pre-printing or since it was pre-printed, the previously mentioned phenomenon of natural backwardation is apt to occur when the inset web is unwound, while if the pre-printed web has become elongated or stretched natural forwardation will 20 take place.

25 In the event of shrinkage of the inset web W, natural backwardation of said web commences and it starts to creep rearwardly with respect to the main webs. Now as the timing arm 69 is 30 mounted on the shaft 34 and rotates with said shaft which is positively driven by the press mechanism, said timing arm will always rotate in synchronism with the press cylinders and will neither accelerate nor de-accelerate.

35 However, as natural backwardation of the inset web W sets in and it starts to fall behind the main webs, the passage of the marks M past the photo-electric cell 65 becomes more and more delayed and the successive energizations of said 40 photo-electric cell become later. At each successive energization of the cell, the arm 69 has approached closer to the contact segment 75 until an energization becomes coincident with the arrival of the timing arm 69 at said segment 75 and 45 contact of the brush 74 on said arm with the segment. Immediately the brush 74 contacts with the segment 75, the electro-magnet 79 becomes energized momentarily so that either the disc 87, or the star wheel 91 (see Figs. 9-10) is turned to 50 rotate the spindle 64, which by the bevel pinions 62 and 61 rotates the worm 57.

55 The worm 57, in being thus rotated, travels or climbs around the periphery of the worm wheel 56, taking with it the casing 55, sleeve 50 and 55 feeding-roller 28 which roller together with the roller 29 is accordingly moved forwardly to advance the inset web into correct register. As the correct register of the inset web is restored, the energizations of the photo-electric cell 65 become 60 earlier until they again occur before the timing arm 69 arrives at the contact segment 76, whereupon the electro-magnet 79 ceases to become energized.

65 In precisely the same way, if the inset web W should have stretched and become advanced by natural forwardation, the energization of the photo-electric cell will take place gradually earlier until they occur when the timing arm 69 is making contact with the segment 76, whereupon the electro-magnet 80 or solenoids 89 will become energized to rotate the disc 87 (or the star wheel 91) and the worm 57 in the opposite direction to retard the feeding-rollers 28 and 29.

70 It will be obvious that either one of the elec- 75

tro-magnets 79 and 80 can be arranged to advance the feeding-rollers 28 or 29, while the other electro-magnet retards said rollers. The reason of this is that although the discs 87 are 5 rotated in the same direction by the energized electro-magnets 79 and 80, the final movement of the worm 57 about the worm wheel 56 will depend upon the arrangement of the pinions 62 on either side of the worm 57, and will also depend upon 10 said worm having left-hand or right-hand threads.

As the inset web is advanced by the feeding-rollers 28 and 29, as described, the part of said web between said rollers and the roll 1 is more or 15 less suddenly shortened and the inset web would be apt to become torn or broken, were it not for the compensating action of the floating tension roller 18 and the brake shoes 6 and 7. When the inset web is more or less suddenly advanced, the 20 compensating tension roller 18 is elevated by the shortening of the loop between the guide rollers 26 and 27. As said roller 18 rises, it swings upwardly the arms 17 and the cam roll 13, and said cam roll by its contact with the arm 12 turns the 25 brake lever 9 upon the pivot 11 and relieves the pressure of the brake shoes 6 and 7 on the brake drum 5a.

Similarly, when the inset web W is retarded by the feeding-rollers 28 and 29, the loop between 30 the guide rollers 26 and 27 is more or less suddenly slackened and elongated, thus causing the compensating tension roller 18 to descend. The descent of said roller lowers the arms 17 and the cam roll 13, and the latter swings the lever 9 upon 35 the pivot 11 to apply the brake shoes 6 and 7 more tightly upon the brake drum 5a. Too sudden movements of the compensating tension roller 18 and correspondingly rapid application of the brake shoes 6 and 7 to the brake drum 5a are 40 prevented by the counterweight 21, the plunger 23 and dashpot 24 as will be readily understood.

During the unwinding of the roll 1, the compensating tension roller 18 rises notwithstanding the fluctuating movements of said roller caused 45 by variations of web-tension set up by the advance and retard movements of the feeding-rollers 28 and 29. At the same time the length of the web W between said roll and the compensating roller 25 increases as the diameter of the 50 roll 1 decreases. The length of the web W between the rollers 25 and 26 remains constant, but as the compensating roller 18 rises, the length of the web W extending between the guide rollers 26 and 27 and around the compensating roller 55 shortens. There is accordingly a balancing of dimensional factors as between the increase in length of the web W between the roll 1 and the roller 25, and the decrease in length of said loop of the web between the guide rollers 26 and 27. 60 The balancing of these dimensional factors governs the register of the pre-printed or pre-marked indications of the web W and maintains said web in its correct pre-set position.

It will, therefore, be clear that the automatic 65 brake, in addition to its functions of register governing in preventing erratic speed or oscillative fluctuations in the inset web W, co-acts with the automatically operative register correction means to maintain said inset web in correct register 70 with the main webs being freshly printed in the rotary web press. The said register correction means comprises the photo-electric cell 65 and its associated circuit "C", the timing means "T" including the insulated segments 75 and 76, the 75 rotating timing arm 69, the electro-magnets 79

and 80 and the discs 87 (or the alternative solenoids 89, plungers 90 and star wheels 91), the spindles 63-64, bevel pinions 61-62, and the infinitely variable or adjustable coupling consisting of the worm 57 and the worm wheel 56, 5 and associated parts.

Attention being directed more particularly to Figs. 9-10 of the drawings, the automatically operative register correction means when fitted with solenoids 89, plungers 90 and star wheels 91 10 operates mechanically to actuate the worm 57 to advance or retard the feeding-rollers 28 and 29 and therewith the inset web W, but otherwise said correction means functions similarly to the electro-magnetic type of register correction 15 means in conjunction with the photo-electric cell 65, said amplifying and relay circuits "C" and said timing means "T" to maintain precisely correct register of said pre-printed inset web, or 20 similarly and/or otherwise marked webs of material.

The inset register and web-tension governing means and the co-acting register correction means herein described, although very simple and inexpensive in comparison with the types of web 25 register controlling apparatus hitherto suggested for, or in regular use with, rotary printing presses or like machines, nevertheless have many important advantages. They are, for instance, automatic in action and they have the great ad- 30 vantage of being positively actuated by and exactly synchronized with the printing cylinders and other mechanism of the rotary press including the inset web and they are solely dependent for their operation on the said press and inset 35 web and they are in no way connected with, driven or governed by motors or other driving means external to or functioning independently of the rotary press, or the inset web.

Moreover, the register and web-tension gov- 40 erning means and the co-acting register correction means may be applied to rotary printing presses already installed in a press room, and they enable four, six or more supplementary coloured monotone or so-called plain pages to be 45 combined with the regular production of the presses. In many cases, the addition of said register and web-tension governing means and co-acting register correction means will enable the installation of extra presses in a printing plant 50 to be postponed, if not altogether avoided. Furthermore, supplementary pre-printed matter especially multi-colour printing can be produced at low or moderate speeds, then re-wound and later associated with the regular press products 55 at the highest speeds of modern rotary web perfecting presses, or the like machines.

It is obvious that various types of automatic braking and/or web tension means may be co-operatively used with my combined automatic 60 register governing and correction means without departing from the spirit of this invention. For the purposes of the foregoing description of construction and/or operation I have shown only 65 one preferred type of automatic braking and/or web-tension governing means. In this invention, the said means are used in a manner not hitherto or previously designated or contemplated and herein are solely used with pre-printed 70 and/or regularly spaced marked rolls of material in web form, more particularly with previously printed inset paper webs as hereinbefore described. The ambit of the invention therefore includes the use of any suitable braking and web- 75

tension means controllable automatically as and solely for the purposes herein described.

- It will be readily understood that my combined automatic register governing and correction means hereinbefore described will function exactly with irreducible minimum of lost motion, time-lag, or slip in the web and/or associated co-operative parts, and that the action of the said combined automatic register governor gearing will be instantaneously co-operative in effecting and maintaining precisely accurate register correction in pre-printed inset webs or the like. Furthermore, the practical elimination of oscillative or erratic backwardation or forwardation ensures that the automatic register correction means and associated interdependent automatic register governing and web-tension and automatic braking means shall operate with comparative infrequency and, therefore, to minimum extent. Freedom from wear and tear in the aforesaid associated and combined web-tension controlling and register governing and correction means, as a result of such relatively infrequent operation, will therefore be manifest and high operative efficiency will be correspondingly evident as an outcome of the synchronized, co-active, and co-operative functions of this invention which habitually produces precise register in a pre-printed inset web or in a second or subsequent printing of a partially printed web and/or in similar, or otherwise marked rolled webs of materials, substantially as described herein.

What I do claim is:—

1. In an apparatus for controlling the feeding of a rolled web as an inset in a main web printed on another machine, including web feeding means designed to be synchronized with the operation of the machine handling the main web, electrically controlled means governed by the movement of the inset web relative to the main web for controlling the rate of feeding of the inset web by the feeding means, a support for a roll constituting a source of supply of the inset web, and automatically compensating web tensioning means intermediate the roll and feeding means for controlling the supply from the roll in accordance with the controlled condition of the feeding means.

2. A construction as defined in claim 1, wherein the automatically compensating web tensioning means includes a brake for governing movement of the supply roll in accordance with the influence of the feeding means on the inset web.

3. A construction as defined in claim 1, wherein the automatically compensating web tensioning means includes a brake for governing the movement of the supply roll, a floating roller operatively connected with the brake and engaging the web intermediate the roll and the feeding means, with said roller movably responding to a slackening of the web under a retarded feeding means or a tightening of the web under an advance feeding means for corresponding brake control.

4. In an apparatus for automatically controlling the delivery of an inset web to a main web controlled in a separate machine, the inset web being provided with register indications, an automatic brake for controlling the delivery tension of the inset web, automatic electro-magnetically controlled feeding means for register connection co-active with the automatic brake and positively driven by and synchronized with the operative mechanism of the main web machine and adapted to advance and retard the moving inset or pre-

printed web, and photo-electric detection means scanning the spaced register indications and governing the operation of the automatic electro-magnetically controlled register correction means by electrical impulses generated in the photo-electric detection means by variations caused in the intensity of light impinging on the photo-electric detection means by movement of said register indications past said photo-electric detection means.

5. In an apparatus for automatically controlling the delivery of an inset web to a main web controlled in a separate machine, the inset web being provided with register indications, an automatic brake for controlling the delivery tension of the inset web, automatic electro-magnetically controlled feeding means for register correction co-active with the automatic brake and positively driven by and synchronized with the operative mechanism of the main web machine and adapted to advance and retard the moving inset web or pre-printed web, means for photo-electrically detecting displacement of the register indications from pre-set position during their movement and for transmitting electrical impulses to the electro-magnetically controlled register correction means when the displacement of said register indications exceeds a predetermined limit in a forward direction or in a backward direction, means for modifying the electrical impulses to enable said impulses to energize the electro-magnetically controlled register correction means, and timing means positively driven by and synchronized with said operative mechanism and adapted to directionally control the transmission of the modified electrical impulses to the electro-magnetically controlled register correction means to thereby govern the actions of said register correction means in advancing or retarding the inset web or the pre-printed web.

6. A construction as defined in claim 5, wherein the timing means comprises angularly spaced insulated contacts connected with the electro-magnetically controlled register correction means and a rotary timing member positively and synchronously driven by the operative mechanism of the said machine and adapted in rotating to complete the circuit of the electrical impulses through said contacts to energize said electro-magnetically controlled register correction means, and wherein the rotary timing member occupies a non-contact or neutral position between the insulated contacts when the register indications pass the photo-electric detection means in correct pre-set position and completes said circuit through the forward insulated contact or through the rearward insulated contact accordingly as said register indications are respectively advanced or retarded from the pre-set position when passing said photo-electric detection means.

7. In an apparatus for automatically controlling the delivery of an inset web to a main web controlled in a separate machine, the inset web being provided with register indications, an automatic brake for controlling the delivery tension of the inset web, a pair of intergeared feeding rollers co-active with the automatic brake and positively driven by and synchronized with the operative mechanism of the said main web machine, an infinitely and oppositely adjustable driving connection associating one of the intergeared rollers with the said operative mechanism and adapted by forward and rearward adjustment to advance or retard said intergeared roll-

ers relatively to said operative mechanism, electro-magnetic means controlling the forward and backward adjustment of said driving connection, means for photo-electrically detecting displacement of the register indications from pre-set position during their movement and for transmitting electrical impulses to the said electro-magnetic means when the displacement of said register indications exceeds a predetermined limit 5 in a forward direction or in a backward direction, means for modifying the electrical impulses to enable said impulses to energize the electro-magnetic means, and timing means positively driven by and synchronized with said operative 10 mechanism and adapted to directionally control the transmission of the modified electrical impulses to the electro-magnetic means to govern the actions of said electro-magnetic means in forwardly or backwardly adjusting said driving 15 connection.

8. In an apparatus for automatically controlling the delivery of an inset web to a main web controlled in a separate machine, the inset web being provided with register indications, an automatic 20 brake for controlling the delivery tension of the inset web, a pair of intergeared feeding rollers co-active with the automatic brake, a driving member operatively connected and synchronized with the operative mechanism of the said main web machine, an infinitely and oppositely adjustable coupling connecting one of the intergeared feeding rollers with the driving member and adapted by forward and rearward adjustment to advance or retard said intergeared rollers 25 relatively to the driving member, electro-magnetic means controlling the forward and backward adjustment of said coupling, a source of illumination adapted to direct a beam of light onto or through the moving web in the course of the register indications, photo-electric detection means positioned to intercept the beam of light after reflection from or transmission through the moving web and adapted on displacement of the moving register indications from pre-set position 30 to send electrical impulses to the electro-magnetic means, means for modifying the electrical impulses to enable said impulses to energize the electro-magnetic means, and timing means positively driven by said driving member and adapted 35 to directionally control the transmission of the modified electrical impulses to the electro-magnetic means to govern the actions of said electro-magnetic means in forwardly or backwardly adjusting said infinitely and oppositely adjustable coupling.

9. In an apparatus for automatically controlling the delivery of an inset web to a main web controlled in a separate machine, the inset web having register indications, a driving shaft, positive power transmitting means connecting and synchronizing the driving shaft with the operative mechanism of the said main web machine, variable speed pre-setting means in said positive power transmitting means, a feeding roller rotatably mounted on the driving shaft, a structure rotatably mounted on the driving shaft and rigidly connected to the feeding roller, a second feeding roller co-acting with said feeding roller on the driving shaft, equal gears interconnecting the feeding rollers, a worm wheel positioned within the structure and rigidly secured to the driving shaft, a worm meshed with the worm wheel and carried by the structure, revolute members operatively connected with the worm and rotatably

mounted in the structure and extending on opposite sides of said structure, electro-magnetic control means positioned on each side of the structure and adapted when separately energized to rotate the revolute member on the corresponding side of said structure, a source of illumination adapted to direct a beam of light onto the moving web in the course of the register indications, photo-electric detection means positioned to intercept the beam of light after reflection from or transmission through the moving web and adapted on displacement of the moving register indications from pre-set position to send electrical impulses to the electro-magnetic control means, means for modifying the electrical impulses to enable said impulses to energize the electro-magnetic means, and timing means positively driven by the driving shaft and adapted to direct the modified electrical impulses to one electro-magnetic control means when the register indications are advanced from the pre-set position and to the other electro-magnetic control means when said indications are retarded in relation to the pre-set position.

10. In an apparatus for automatically controlling the delivery of an inset web to a main web controlled in a separate machine, the inset web having register indications, a driving shaft, power transmitting means positively and synchronously connecting the driving shaft with the operative mechanism of the said main web machine, variable speed pre-setting means in said power transmitting means, a feeding roller rotatably mounted on the driving shaft, a skeleton structure rotatably mounted on the driving shaft and rigidly connected with the feeding roller, a second feeding roller co-acting with said feeding roller on the driving shaft, equal gears interconnecting the feeding rollers, a worm wheel positioned within the skeleton structure and rigidly secured to the driving shaft, bearing supports within the skeleton structure, a worm meshed with the worm wheel, coaxially aligned shafts on opposite ends of the worm, gears on the coaxially aligned shafts, a transverse shaft rotatably mounted in said structure adjacently to each end of the worm, said shafts being respectively extended on opposite sides of the structure, gears on the transverse shafts meshed with the gears on the coaxially aligned shafts, electro-magnetic control means fixed concentrically about the driving shaft in stationary positions on opposite sides of said structure, rotatable means on the extended ends of the transverse shafts adapted to be revolved by the electro-magnetic means to turn said transverse shafts, photo-electric scanning means adapted on displacement of the moving register indications from pre-set position to send electrical impulses to the electro-magnetic control means, means for modifying the electrical impulses, a stationary insulating block fixed concentrically about the driving shaft, a pair of angularly spaced conducting segments mounted in said block and connected respectively to the oppositely positioned electro-magnetic control means, and a rotary conductive arm mounted on the driving shaft and adapted by contact with one of the conducting segments to direct the modified electrical impulses to one electro-magnetic control means when the register indications are advanced from the pre-set position and by contact with the other of said segments to direct said impulses to the other electro-magnetic control means when said indications are retarded from the pre-set position.

11. A construction as defined in claim 10, wherein the electro-magnetic control means comprise annular peripherally-wound electro-magnets or segmental electro-magnets having angularly spaced energizing coils, and wherein the rotatable means on the transverse shafts consist of disks of magnetic material which are carried by said structure in a circular orbit about the axis of the driving shaft and move without contact around peripheral channels having for their sides magnetic plates forming the poles of the electro-magnets.

12. A construction as defined in claim 10, wherein the electro-magnetic control means comprise solenoids disposed concentrically about the driving shaft in angularly spaced positions and provided with plungers of magnetic material which are protruded when the solenoids are energized and are thrust backwardly into said solenoids by cams fixed to the hollow or open structure, and wherein the rotatable means on the transverse shafts consist of star wheels which are carried in a circular orbit about the axis of the driving shaft and are adapted to contact with and be rotated by the plungers when said plungers are protruded from the solenoids.

13. In an apparatus for automatically controlling the delivery of an inset web to a main web controlled in a separate machine, means for advancing or retarding the moving web comprising a driving shaft positively connected and synchronized with the operative mechanism of the said machine; a feeding roller rotatably mounted on the driving shaft, a second feeding roller co-acting with said roller on the driving shaft, equal gears interconnecting the said feeding rollers, a worm wheel rigidly fixed to the driving shaft, and a worm meshed with the worm wheel and positively connected with the feeding roller on the driving shaft.

14. Apparatus according to claim 13, wherein the worm and worm wheel are of self-locking type and form a driving connection between the driving shaft and the feeding roller on said shaft,

and wherein the worm on being rotated in either direction climbs around the periphery of the worm wheel and rotates the feeding roller upon the driving shaft and advances or retards said feeding roller and the coacting feeding roller relatively to said driving shaft and to said operative mechanism accordingly as the worm climbs forwardly or backwardly around the worm wheel relatively to the direction of rotation of said worm wheel.

15. In an apparatus for automatically controlling the delivery of an inset web to a main web controlled in a separate machine, means for advancing or retarding the moving web comprising a driving shaft positively driven by and synchronized with the operative mechanism of the said main web machine, a feeding roller rotatably mounted on the driving shaft, a hollow or open structure rotatably mounted on the driving shaft and rigidly connected with the feeding roller, a second feeding roller co-acting with the feeding roller on the driving shaft, equal gears interconnecting said feeding rollers, a worm wheel fixed securely to the driving shaft and positioned within the hollow or open structure, bearing supports within said structure, a worm journaled in the bearing supports and meshed with the worm wheel, gears on the opposite ends of the worm, a transverse shaft rotatably mounted in the hollow or open structure adjacently to one end of the worm and extended on one side of the structure, a transverse shaft rotatably mounted in said structure adjacently to the other end of said worm and extended on the opposite side of the structure, gears fixed to the transverse shafts and meshed with the gears on the worm, and means on the projecting ends of the transverse shafts whereby said transverse shafts may be rotated independently to rotate the worm in opposite directions to climb forwardly or backwardly around the worm wheel and respectively advance or retard said structure and said feeding rollers relatively to the driving shaft.

THOMAS HAMILTON GROZIER.
